METHOD AND MEANS FOR WELL DEVELOPMENT

Reuben Richard Schweitzer and Chester Royal Sundquist, Norfolk, Va.; said Sundquist as signor to said Schweitzer

Application May 21, 1934, Serial No. 726,818

10 Claims. (Cl. 166—20)

This invention is directed to a method and apparatus for the development of water wells of the graveled type.

In providing for the development of water wells, 5 the initial operation is the boring operation, during which the slush is delivered into the well for the purpose and with the effect of providing a mud layer over the sand stratum encountered in the boring to prevent collapse of this stratum 10 during the well formation. As the sand stratum is the water-producing area, this stratum must be held by the inserted gravel to substantially the desired diameter, for if continued collapse of the sand stratum is permitted, the interstices 15 between the gravel, forming the filtering media, will be seriously impeded and the sand possibly reach the screen with deleterious effects on the pump.

It has been proposed in a well of this type to 20 hydraulically displace the mud layer of the well, particularly over the sand stratum, and simultaneously replace the mud layer and such of the sand as may be washed out in the hydraulic action with a gravel body which serves to support the sand stratum against collapse and at 25 the same time afford the desired filtering medium for the water. It is, of course, well known among engineers that the area of the filtering medium directly affects the capacity of the well, the same 30 as in all filters. Therefore, the larger the surrounding area between the sand stratum and the screen, the larger the flow of water; that is to say, the larger the point of separation or separating area the less likelihood of moving the 35 sand and the less likelihood of causing the sand to penetrate the gravel and fill up the interstices. This will be evident from the known fact that the friction is reduced according to the square 40 of the velocity and the velocity reduced directly according to the area. For instance, a 32 inch diameter circle would have four times the diameter area as an 8 inch diameter circle and, therefore, the velocity to move the sand would be only one-fourth in the 32 inch diameter circle, but 45 the friction on the sand created by the velocity would be reduced to one-sixteenth of the velocity around an 8 inch circle, as the square of the difference of the area would indicate the friction on the sand.

50 It has been proposed to accomplish this enlargement or under-reaming by mechanical under-reamers but such operation has proven decidedly objectionable, owing to the necessity of replacing the sand displaced by the mechanical 55 under-reamer with heavy drilling mud, creating

a mud-plastered wall on the face of the underreamed portion of the sand, with the attendant extreme difficulty if not impossibility of removing this mud wall after the space has been filled with gravel in the ordinary manner and the well 5 screen proper has been placed in position.

Even in hydraulic action to displace the mud wall, with the consequent and absolute certainty of the simultaneous displacement of more or less of the sand, difficulty has been encountered in 10 removing the sand particles so displaced to an extent to prevent accumulation of these sand particles in the interstices of the gravel bed to a degree to retard the flow of water through such 15 gravel bed.

The method heretofore proposed for the removal of the mud and sand displaced through the hydraulic action has been through a flotation process and experience has demonstrated that a definite part of the sand so displaced will not 20 readily yield to the flotation effect and will gradually settle into the gravel bed. Therefore, the flotation method of removing the displaced mud and sand is not as completely effective as is desired, with the result that the otherwise effective 25 capacity of the well is somewhat, and at times very materially, decreased.

The primary object of the present invention is the provision of means by which the hydraulic action necessary to remove the mud and displace 30 the sand in the sand-bearing stratum is utilized to automatically accommodate itself for the washing of the mud from the sand-bearing stratum and the displacement of sufficient of the sand-bearing stratum to constitute an under-reaming of the 35 well in the sand stratum area, with the automatic control of the hydraulic action gradually increasing its effective range laterally of the well as the sand is displaced, with the lateral range 40 of the hydraulic force continually increasing in proportion to the displacing of the sand until the maximum limit of under-reaming desired has been reached.

A further object of the present invention is the provision of means whereby the flotation medium 45 is subjected to pressure withdrawal in part, with the effective withdrawal area so arranged in relation to the area of hydraulic action that the particles of sand suspended in the body of water incident to the turbulence during hydraulic action will be to a large degree compelled to move 50 upwardly to the surface of the well for discharge, and with the further relation between the effective area of the withdrawal means and the turbulent body incident to hydraulic action so 55

located as to have the desired effect on the sand particles and without corresponding effect on the deposited gravel.

A further object of the present invention is the provision of means for delivering the desired gravel into the turbulent area of the hydraulic action and at a point of delivery so related to the turbulent body as to insure that the sand displaced from the sand stratum by the hydraulic action will be replaced by the gravel, so that on completion of the under-reaming the confining wall of the sand stratum defining the under-reamed area will be effectively supported by a gravel body providing a clean filtering body between such sand wall and the screen.

As the result of the combined method and apparatus, the mud is washed from the sand stratum of the well, the sand stratum is under-reamed, a portion of the refuse so displaced is carried to the surface of the well by the flotation process, and those particles of the sand which would ordinarily not respond to the flotation process are withdrawn under suction pressure from the hydraulic area, together with the deposit of gravel during these operations to insure a proper deposit of the gravel body and at the same time maintain this gravel body as free as possible of particles of sand and the like which would otherwise tend to materially clog or interfere with the passage of water through the gravel body.

The invention is illustrated in the accompanying drawing, in which:

Figure 1 is a view in vertical section, partly in elevation, illustrating the means for carrying out the method of well development forming the subject-matter of the present invention, the flexible jet conduits being shown in the position initially occupied at the start of the hydraulic action.

Figure 2 is a broken view showing a portion of the well formation and illustrating the automatic accommodation of the hydraulic action for the under-reaming operation.

Figure 3 is a plan of the hydraulic head.

Figure 4 is a longitudinal section of the hydraulic conduit.

The bored well as completed by the boring action is illustrated in Figure 1, in which it will be noted that there are presented well defined layers of the various materials constituting the formation, among which are indicated a water-bearing sand stratum 1 which constitutes the main area through which the water is delivered to the well. Following the boring operation, the bore of the well is lined with a layer of mud 2 deposited thereon during the boring operation, particularly with a view to preventing the collapse of the sand in the water-bearing stratum during the initial formation of the well. This mud layer is practically impervious to the free flow of water and must obviously be removed at least throughout the extent of the water-bearing stratum 1.

It has been found from experience that the most effective way of removing the mud wall is by hydraulic action, the jet streams of which are directed at an effective angle to displace or wash away this mud, with the hydraulic head gradually moved upwardly to displace the mud wall throughout the desired area. Of course, as the mud wall is removed from the sand-bearing stratum, there is liability, particularly under the hydraulic action, of the collapse of the sand which naturally would accumulate in the bottom of the well with obvious disadvantage, and to

overcome this collapse it has been previously proposed to introduce gravel or other filtering media into the well, maintaining the level of the accumulated gravel substantially coincident with or slightly above the plane of action, to insure that as the wall of the well is displaced by the hydraulic action, such displaced material will be automatically replaced by the gravel or other filtering media.

It is naturally desirable to provide within limits a material enlargement throughout the height of the sand stratum constituting the water-bearing sand in order that the final diameter through this sand stratum shall be very materially increased over the diameter of the well bore. This is known as under-reaming and obviously tends to increase the flow of water as the larger the area of the gravel wall through which the water flows the greater the flow of water in a given time. The difficulty of this under-reaming step, however, has been, first, in taking care of the introduction of the gravel body to prevent collapse of the sand wall and further to insure that the sand particles separated from the sand stratum in under-reaming are prevented from accumulating in the gravel body to interfere with the free flow of water therethrough.

An essential feature of the present invention is the provision of a hydraulic method and means which will afford an effective washing away of the mud wall and which will provide for an under-reaming of the selected sand stratum, with the under-reaming operation automatically accommodating itself as the under-reaming proceeds to insure not only an effective direction but an effective delivery of the hydraulic jets in operation.

The hydraulic action in the under-reaming step of the present invention is carried out through the use of a series of jets and the sand and other materials displaced by this hydraulic action are replaced substantially simultaneously with gravel introduced from the surface of the well. As this gravel enters the line of stream of water from the nozzles, it has a decided abrasive effect on the sand body being cut away and thus materially assists in the under-reaming operation and not only assists in this operation but tends to a more effective placement of the gravel to replace the dislodged sand particles.

In carrying out this step of the method, there is provided a hydraulic head 3 of hollow construction, the bottom wall 4 of which preferably inclines slightly upwardly from the center and the side walls 5 of which preferably incline upwardly and inwardly, or in other words, converge upwardly from the bottom. It will, of course, be understood that while preferring the hydraulic head with the inclined walls as described, the use of a head with walls in other angular relations is contemplated. The head carries an upstanding sleeve extension 6 interiorly threaded for the reception of casing sections 7 though any type of connection is contemplated, which, of course, are connected end to end to provide the desired length of conduit for lowering the head to the desired depth in the well.

The side walls 5 of the head are provided with openings 8 having exterior nipples 9 on which are removably secured hydraulic conduits 10. These conduits form an essential feature of the present invention. They are constructed of appropriate material which will insure them maintaining a straight length in the absence of resistance while yet permitting them to flex or bend in any portion

under resistance. Thus, the conduits are neither completely flexible or completely rigid but partake of both in that they are capable of being flexed and yet have an inherent tendency to straighten out in the absence of resistance to such movement.

While it is preferred that the hydraulic conduits 10 be formed to provide a nozzle or jet effect to a tapered bore, such, for example, as indicated in Figure 4, it is nevertheless to be understood that a hydraulic conduit of uniform bore throughout may be used. The conduits are, of course, to be constructed to straighten out on release of resistance through their inherent construction and this straightening-out function will, of course, be materially assisted by the passage of water therethrough. Furthermore, the conduits are designed to yield or flex under any reasonable or excessive resistance which will prevent their assuming a straight relation, though the conduits are to be so constructed that as they are moved gradually upwardly throughout the sand stratum to be under-reamed, the comparatively slight resistance encountered by the ends of the conduits in this movement will not tend to materially flex them. In other words, where the conduits have assumed a straight relation incident to their reaming-out operation of the sand necessary to permit this straight relation, they will ordinarily maintain this relation during upward movement necessary to under-reaming action in the sand stratum and will not again be flexed until they encounter, in the upward movement of the head, the clay or other relatively hard stratum immediately above the sand stratum being under-reamed.

It is, of course, to be noted that the hydraulic head is provided in its walls 5 with a sufficient number of openings or outlets 8 to permit the use of a considerable number of the conduits 10 which in the completed structure radiate from the head in all directions and are preferably so closely associated at the head that the outlet or delivery ends 11 are not widely separated. It is, of course, to be understood that the hydraulic head and therefore the hydraulic conduits 10 are designed to be raised gradually during the under-reaming of the sand stratum and it is also contemplated that during this upward movement or while the head is at rest during the under-reaming action, the head and nozzles may be rotated either partially or completely in order to insure a completely effective searching of the jets of water throughout the full area of the sand stratum being subjected to the under-reaming action.

As mechanism for imparting rotation and upward movement to reamers and other well accessories are quite common in the art and as such details form no material part of the present invention, no illustration thereof is deemed necessary. It is sufficient to direct attention to the fact that the hydraulic head and hydraulic conduits are designed to be gradually moved upward in use and may, if desired, be given a rotary movement for increased effect in under-reaming.

The sleeve 6 is also provided with jet outlets 12 which are directed upwardly at a somewhat less angle to the vertical than that of the conduits 10, these jets 12 serving a particular purpose to be hereinafter described.

In connection with the hydraulic member described, a casing 13 made up, of course, of sections designed for removable connection is arranged to encircle the hydraulic casing 7. The

casing 13 has a diameter exceeding that of the casing 7 and provides between it and such casing 7 a passage 14 opening at the top of the well and opening at the bottom of the well at a point above the hydraulic head. This casing 13, or more particularly the passage 14 between the casings 7 and 13, is designed to provide for the pressure withdrawal of a very considerable if not greater portion of the water and materials dislodged by the jets in the under-reaming action, this casing 13 being under appropriate suction and hereinafter referred to as the withdrawal pipe.

A pipe 15 also forms a part of the apparatus with which the present invention is concerned, this pipe being of comparatively small diameter, at least with respect to the hydraulic casing 7, and being designed to provide a means for delivering gravel to the bottom of the well for the development of the filtering area. The pipe 15 terminates at its outlet end 16 below the outlet end of the withdrawal casing 13 and it is, of course, to be understood that the gravel is introduced through this pipe with water and under sufficient pressure to properly deliver and distribute the gravel beyond the outlet end 16 of the pipe.

In carrying out the method and utilizing the apparatus hereinbefore described, the hydraulic head is lowered into the well through an appropriate length of hydraulic casing 7 until the particular sand-bearing stratum 4 is reached. As the hydraulic conduits 10 together define a diameter substantially commensurate with the desired diameter of the under-reamed chamber, it is, of course, apparent that during the delivery of the hydraulic element into the well and when such element is initially positioned at the bottom of the well or adjacent the particular said stratum, these hydraulic conduits are turned upwardly, being flexed, of course, by contact with the wall of the well.

The water under pressure is then delivered through the casing 7 and into the head 3. This water finds its way under considerable pressure through the hydraulic conduits 10 and through the preferably restricted jet outlets 12, being also preferably delivered through an opening or openings 17 in the bottom of the head. The initial effect of the water jettied through the hydraulic conduits 10 is upwardly, directly in line with the mud wall. This operation cleans the mud wall away from the selected sand stratum and naturally will start to excavate the sand underlying the mud wall which has been cleaned away.

As the sand is displaced under the hydraulic action, the hydraulic conduits 10 tend to straighten out. This deflects the jet of water flowing through the conduits or each of them outwardly with respect to the bore of the well and as the displacement of the sand under the jets is progressing, the conduits tend more and more to seek a normal straight position during which the sand is displaced laterally and progressively until the maximum or straight position of the conduits is reached, when the effect of the water jets is more nearly laterally and the enlargement or under-reaming of the sand stratum is completed at the effective limit of the water jet with the hydraulic conduits 10 in their straight positions. The hydraulic head and conduits are, of course, gradually raised to insure a complete under-reaming throughout the

height of the sand stratum and during this upward movement, either continuously or intermittently, the hydraulic head and conduits may be rotated, as previously stated.

5 During the entire hydraulic action, gravel is being delivered into the well through the space 15. This gravel incident to gravitational action and to the movement of the gravel under the turbulence of the water in the hydraulic area will 10 spread out to take the place of the displaced sand. This spreading out of the gravel body is in effect substantially simultaneous with the displacement of the sand and as the sand displacement continues, the direct substitution of the 15 gravel body also continues until finally, when the under-reaming operation is completed, all displaced sand has been replaced by the gravel body.

20 A portion of the displaced material, particularly the mud, is floated to the surface of the well under the natural upward movement of the water delivered for the hydraulic action. It has been found, however, from experience that there is a proportion of the material of the sand stratum, that is, certain particles ordinarily found in such stratum, which while readily moved and held more or less in suspension within the direct 25 turbulent area of the hydraulic action, will not respond to a natural flotation action and will 30 not, therefore, float upwardly and out the top of the well but will tend to eventually gravitate to the gravel bed. These particles have a tendency to effect a clogging or partial closing of the interstices between the gravel of the gravel bed 35 and thus interfere with the flow of the water through such gravel bed and correspondingly reduce the volume capacity of the well.

40 It will, of course, be apparent that the turbulence created through the action of the water in the under-reaming process will naturally tend to substantially classify the solid materials in the turbulent area. The finer muds and finer sands would quickly reach the top of the area, the medium and coarser sands will reach substantially 45 the mid-height of the area, and the heavier gravels and filtering media will naturally, owing to their gravitational action, take their place at the bottom of the area.

50 To avoid this result, the withdrawal function of the pipe 13 is utilized. As this pipe is under sufficient suction to cause a steady withdrawal of the water and other material in the well to the capacity of the pipe, it follows that, except under predetermined conditions, the suction or withdrawal effect of the pipe 13 might seriously displace and as a matter of fact tend to a withdrawal 55 of no inconsiderable part of the gravel or filtration bodies introduced through the pipe 15. As it is important to avoid this result, it follows, 60 that the pipe 13 must be arranged so that its lower or inlet end is accurately placed with relation to the turbulent area of the hydraulic action, under any varied conditions in the well being developed.

65 In other words, the lower or inlet end of the pipe must be so arranged that it will serve to draw into the pipe, under the suction provided, those particles floating in the turbulent area which are light enough to be held in more or 70 less suspension in the water in such area and yet too heavy to be floated to the surface in the natural flotation movement. The particular particles under consideration are those of the sand stratum which experience has demonstrated will 75 not float to the surface and which will otherwise

tend to gravitate to the gravel bed. With this purpose in view and in the light of the classification of materials in the turbulent area as above pointed out, it is proposed that the inlet of the withdrawal pipe 13 shall be located in the 5 mid-area of the turbulent body which will insure the withdrawal, under appropriate suction, of the finer muds and sands and of the coarser sands, all of which are located either at substantially the middle area or above such area of the turbulent body.

Therefore, the lower or inlet end of the withdrawal pipe must be so located and changed with respect to the turbulent area that these particles of sand, grit and like material will be drawn into 15 the pipe and so brought to the surface of the well for discharge without, however, affecting the gravel or other filtration bodies. In actual practice, this can be readily accomplished by lowering the pipe and starting the action and determining by the outflow whether the sand particles are being reached without affecting the gravel. If the gravel is being withdrawn, the pipe is raised slightly until practically no gravel is discharged through the pipe. In any event, the essential 20 feature in this particular is that the inlet end of the withdrawal pipe must be so located with respect to the turbulent area of the hydraulic action as to effectively withdraw those particles at least of the displaced sand which would not 25 otherwise yield to the flotation action without any appreciable disturbance and particularly without any considerable withdrawal of the gravel of the gravel body.

Under the hydraulic action of the hydraulic 35 jets 10 and the consequent turbulent action of the hydraulic area, the sand and like refuse particles would naturally tend to eddy toward the center and thus accumulate in line with the hydraulic head. In order, however, to prevent such accumulation and to maintain a more or less turbulent and suspension relation of the particles in the water, the jets 12 are provided. These jets direct water under pressure more or less upwardly and thus tend to keep these particles, which would 40 otherwise accumulate under eddy action at the center of the turbulent area, in more or less active movement in an upward direction, so that they are more easily and in greater volume subject to the withdrawal action of the pipe 13. 50

After the well is completed by the under-reaming and graveling, the usual screen in conventional form and of appropriate area is bailed down in the conventional way through the gravel cylinder to its appropriate position and the well is 55 complete.

The hydraulic casing or conduit 1, the gravel conduit 15 and the withdrawal pipe 13 are appropriately connected at the top of the well by an element indicated at 18 which may be provided with lifting means 19 so that all these parts may be moved upwardly as desired in operation. Of course, it is understood that the hydraulic head is gradually moved upwardly during the hydraulic action in order to effectively remove the mud wall from the desired sand stratum and under-ream such sand stratum throughout the desired vertical extent. If the hydraulic conduits 10 yield or flex sufficiently to permit their movement to a position 60 commensurate with the normal bore of the well, they may be withdrawn with the head, otherwise these conduits may, in the upward movement of the hydraulic head, be broken off and permitted to remain in the well, as they will not seriously 65

affect the flow of the water in any particular.

The method consisting in the hydraulic under-reaming of the well with the automatic combination of the hydraulic action to such under-reaming action and the forced withdrawal of certain particles dislodged in the under-reaming which are incapable of flotation to the surface of the well, provides for an extended area of the chamber in the sand-bearing stratum to materially increase the quantity flow of the water and furthermore in the accumulation in this chamber of a gravel body which not only supports the wall of the chamber against collapse but acts as a filtration for the incoming water, with this gravel body maintained in a natural open condition without material clogging of the sand and other particles to interfere with water flow. There is thus produced a well presenting the maximum capacity in volume and which will remain at the maximum for a materially longer time by reason of the fact that the interstices of the filtration body are not interfered with. The method including the step of withdrawing the displaceable but non-floatable particles of sand from the sand stratum results in a material increase in the volume flow of the water as it prevents the accumulation of these particles in the water body and the consequent interference with the maximum flow of water.

While the invention is described in connection with wells as initially developed, it is quite apparent that the hydraulic under-reaming action is equally effective with wells which are already in production but in which the volume flow is materially less than that expected from the nature of the formation in which the well is located. In these uses, the screens in the well may be withdrawn, the hydraulic element introduced and the well hydraulically under-reamed according to the method of this invention, with the result already demonstrated in practice of materially increasing the volume flow from the particular well.

Further, while the method and apparatus are particularly applicable to water wells, it is not intended to be limited to this use, as it is designed for use in connection with any well designed to produce a fluid flow and in which such fluid flow can be increased by the use of the method and means described.

What is claimed as new is:

1. A means for hydraulically under-reaming a bored well, including a hydraulic head for the reception of fluid under pressure, outlets leading from the head, and flexible conduits leading from the outlets and radiating from the head, the distance between the outlet ends of the conduits being materially greater than the normal diameter of the bore of the well, said conduits being of a character to automatically assume an inherently straight relation when relatively free of resistance.

2. A means for developing a bored well, including a hydraulic head for the reception of fluid under pressure, hydraulic conduits radiating from the head and in communication therewith, the diameter of the head and conduits together materially exceeding the normal diameter of the bore of the well, said conduits being inherently straight and capable of flexing under pressure without interfering with the fluid discharge, and a conduit terminating above the head and providing a passage for the delivery

of filtering media to the area of the well including the head and hydraulic conduits.

3. A means for developing a bored well, including a hydraulic head for the reception of fluid under pressure, hydraulic conduits radiating from the head and in communication therewith, the diameter of the head and conduits together materially exceeding the normal diameter of the bore of the well, said conduits being inherently straight and capable of flexing under pressure without interfering with the fluid discharge, and a withdrawal pipe subject to suction and terminating within the well in an inlet above the hydraulic head.

4. A means for developing a bored well, including a hydraulic head for the reception of water under pressure, hydraulic conduits radiating from the head and in communication therewith, the diameter of the head and conduits together materially exceeding the normal diameter of the bore of the well, said conduits being inherently straight and capable of flexing under pressure without interfering with the water discharge, and a withdrawal pipe subject to suction and terminating in an inlet between the delivery end of the filtering media conduit and the hydraulic head.

5. A means for developing a bored well, including a hydraulic head open to water under pressure, a series of hydraulic conduits radiating from the head and in open communication therewith, said conduits being inherently straight and capable of flexing under pressure without interfering with water flow, the distance between the discharge ends of the opposing conduits exceeding the normal diameter of the bore of the well, a conduit leading into the well and terminating above the head for the delivery of gravel to that portion of the well affected by hydraulic action, means carried by the head for directing jets of water upwardly with respect to the head to maintain the particles dislodged by the jets of the hydraulic conduits in suspension in the water, and means arranged beyond the gravel conduit for forcibly withdrawing the suspended particles to the top of the well.

6. A means for developing a bored well, including a hydraulic head open to water under pressure, a series of hydraulic conduits radiating from the head and in open communication therewith, said conduits being inherently straight and capable of flexing under pressure without interfering with the water flow, the distance between the discharge ends of the opposing conduits exceeding the normal diameter of the bore of the well, a conduit leading into the well and terminating above the head for the delivery of gravel to that portion of the well affected by hydraulic action, means carried by the head for directing jets of water upwardly with respect to the head to maintain the particles dislodged by the jets of the hydraulic conduits in suspension in the water, and means arranged beyond the gravel conduit for forcibly withdrawing the suspended particles to the top of the well, said means having an inlet end in such relation to the hydraulic head as to permit withdrawal of the jet-dislodged particles without creating withdrawal action on the incoming gravel.

7. A means for developing a bored well of the gravel type, including a member for creating a hydraulic action against the wall of the well bore in any predetermined area of such bore, said member including jet-directing means having a length exceeding the diameter of the bore of the

- well and inherently straight when free of resistance, said jet-directing means being capable of flexing under resistance, a pipe for delivering water under pressure to the hydraulic member, a casing encircling and spaced from said pipe provided for the delivery of gravel to that area of the well within the hydraulic action, and a withdrawal pipe open to suction and having an inlet end terminating above the hydraulic member for the forcible withdrawal of dislodged material not susceptible to discharge by flotation.
8. A means for developing a bored well of the gravel type, including a member for creating a hydraulic action against the wall of the well bore in any predetermined area of such bore, said member including jet-directing means having a length exceeding the diameter of the bore of the well and inherently straight when free of resistance, said jet-directing means being capable of flexing under resistance, a pipe for delivering water under pressure to the hydraulic member, a withdrawal casing encircling and spaced from said pipe provided for the forcible withdrawal of dislodged material not susceptible to discharge by flotation, a pipe open to pressure and having an outlet end terminating below the withdrawal pipe for the delivery of gravel to that area of the well within the hydraulic action, and inde-

pendent jet means carried by the member for maintaining the turbulence at the hydraulic area to present dislodged material within the effective range of the withdrawal pipe.

9. A method of under-reaming a bored well, consisting in directing a plurality of jets initially against and at a slight angle relative to the wall of the well bore and upwardly, and thereafter increasing the angular relation of the jets relative to the well bore as more and more of the material of the bore is displaced.

10. A means for under-reaming the water-bearing stratum of a water well, comprising jetting conduits having an inherent tendency to assume a maximum angle position approximating a right angle to the wall of the well bore, the normal wall of the well bore serving to hold the jets at a minimum angle, the jet impact increasing the displacement of material as the jetting conduits move from the minimum angle position to the maximum angle position, the displacement of the material from the wall under the jet impact serving to permit the jetting conduits under their inherent tendency to move from the minimum angle position to the maximum angle position.
